UNITED STATES PATENT OFFICE

2,120,231

RESPIRATOR

Harvey S. Cover, South Bend, Ind.

Application December 26, 1935, Serial No. 56,255

9 Claims. (Cl. 128—146)

My invention relates to improvements in respirators and has for an object the production of an improved device to be used for protecting the user from dust, smoke, and noxious gases of various kinds.

A specific object is the provision of a respirator provided with filter boxes which are compact and space-saving and at the same time are effective to admit the desired flow of air. Space-saving is accomplished by providing a thumb rest, or equivalent means, on the outside face of the inner element of the filter box, so the middle finger of the left hand can be placed in the air opening in this element as a support, and the thumb 10 rested against or supported against the above mentioned thumb rest in such manner as to be able to screw the lid or outer element on or off the inner element, while at the same time the outer element may extend clear across or over the margin of the inner element. Heretofore, in the art, this has been impossible to accomplish when both elements have been grasped at the outer margin of their circumferences.

Another object is the provision of a respirator which has the advantage of having filter boxes or chambers which are removable and also adjustable in accordance with sight requirements among other reasons.

Another object is the provision of a respirator provided with filter boxes which are compact and space-saving and at the same time effective to admit the desired flow of air.

Still another object is the provision of a reversible respirator provided with filter boxes which may be adjusted to permit reversibility without any interference with vision, etc. For example, in the form shown, I have disclosed a reversible respirator having filter boxes which may be adjusted to top, intermediate, or low positions. This respirator may be reversed without any disadvantages whatever as to filter boxes which have the advantage of being capable of adjustment to any position.

My invention makes possible the use of an unusually large diameter of filter box in a respirator and any disadvantages in the way of vision are eliminated by virtue of the adjustability of the filter box.

Another object of my invention is the provision of a compact and light respirator provided with filter boxes of the character described, and a respirator having desirable audibility without any specially designed valves, such as a vibrating diaphragm.

Another object is the provision of an exhaust

valve provided with a minimum of contact between the valve and valve seat whereby any danger of sticking or sluggishness is eliminated.

A further object is the provision of a filter box provided with corrugations arranged to admit the air in a most efficient manner and one which has the requisite strength.

A still further object is the provision of a device of the character described which is easy of assembly and application and which is relatively inexpensive in cost of manufacture.

My invention may be best understood by reference to the accompanying drawings, in which:

Fig. 1 is a front view of the device as applied to a face, showing the filtering boxes in intermediate position;

Fig. 2 is a similar view to that of Fig. 1, showing the box on the left side (looking at the drawings) in low position, and the other box in intermediate position, either of the boxes being capable of being moved to high position;

Fig. 3 is a section taken on the line 3—3 of Fig. 1;

Fig. 4 is a view of the outside face of the inner element of one of the filter boxes;

Fig. 5 is a section on the line 5—5 of Fig. 3;

Fig. 6 is a section taken on the line 6—6 of Fig. 5, showing the face of the inner element of the box opposite to that face shown in Fig. 4;

Fig. 7 is a face view of the outside of the outer element of the box;

Fig. 8 is a view substantially similar to Fig. 5, showing some of the parts disassembled; and

Fig. 9 is a perspective view illustrating the manner of adjustment.

The preferred form of my invention which has been selected to illustrate the principle of said invention, includes a respirator body 15, provided with cut-outs 16 to accommodate the nose of a wearer. Also in the form shown a guard of cloth or other material is shown worn in conjunction with the respirator. This and others of the inventive features in the device shown have been covered in previous applications filed by me. The cut-outs 16 are particularly shown in Figs. 5 and 3. It will be noted that a cut-out is provided at the top and also at the bottom of the respirator body 15 which makes it possible to invert the body.

The body 15 is provided with a bulbous valve 50 housing 17 having exhaust openings 18 as shown particularly in Figs. 1, 3, and 5. In the form shown it will be noted that one of the openings 18 is superimposed over the other. Located in the housing 17 is a valve seat 19 which in the form 55

shown is oval and is provided with a flange 20. The valve seat 19 is retained in place as shown particularly in Figs. 3 and 5 by an inner retaining shoulder 21 and outer retaining shoulders 22 as shown in Figs. 3 and 5. The seat 19 is concaved as at 23, as shown in Figs. 3 and 5, and is provided with valve openings 24. The valve seat 19 is provided around the openings 24 with sharp flared edges 25, particularly shown in Fig. 3. By 10 the arrangement of the sharp flared edges 25 with the valve 26 there is only a minimum of contact between the valve and valve seat in the valve area, and this arrangement of the sharp flared edges has the advantage of eliminating any 15 tendency there might be for the valve to stick or adhere momentarily to the valve seat or to act sluggishly, for example, under unusual atmospheric conditions.

The valve 26 is a flat valve which is oval in 20 form as described in previous applications filed by me and is attached in the central area of the valve as shown in Figs. 3 and 5. By virtue of the arrangement as disclosed in the previous applications, the valve 26 lies against the valve seat 25 with a minimum of contact in the valve opening area. The valve is normally closed to seal off tightly the outside air, and at the same time has a sensitive action to meet all the needs of expiration.

30 The body portion 15 looking at the drawings as shown in Figs. 1 and 2, has an integral right wall 28 and integral left wall 29, and the walls 28 and 29 are each provided with an opening 30 as shown in Fig. 5. Adapted to be secured to each 35 of these walls 28 and 29 in the area of the opening 30 is a filter box. There are two of these filter boxes and a description of one of these boxes and the means for connecting and supporting it to the body will suffice, the boxes and connecting and supporting means being the same in 40 each case.

Adapted to fit into one of the openings 30 is a flanged, threaded locking cap 31 having an opening 32, which cap is also adapted to fit into an 45 off-center opening 33 in the base of an inner element 34, which, with an outer element 35, comprises each of the two filter boxes 36. These parts are clearly shown in Figs. 3, 5, and 8. For securing the inner element 34 to the wall 28, for example, a threaded locking ring 37 is adapted to be screwed on the flanged locking cap, the ring 37 having thumb and finger cut-outs 38 for convenience in turning as shown in Fig. 6. Each of the inner elements 34 has a threading flange 39 50 and a retaining flange 40 as shown in Figs. 4, 5, and 6, perpendicular to said flange 39, which flange 40 has the advantage of properly positioning the filter material in the filter box, as will be more evident hereinafter. Each of the inner elements 34 is provided with three pockets, 41, 42, and 43, as shown in Figs. 4 and 6; to wit, a top pocket 41, an intermediate pocket 42, and bottom pocket 43, arranged in a radial manner in relation to the opening 33 to accommodate one of the 55 nuts 44 which secure one end of a strap 45 to the body 15 and also provide raised portions to keep the filter element away from the side wall of the inner element. The arrangement just described has the advantage among others that by 60 unscrewing the ring 37 the filter box may easily be detached from the body 15, and furthermore may be adjusted to any position desired. For example, in Fig. 1, both of the filter boxes are in intermediate position, whereas in Fig. 2 one of the boxes is in intermediate position and the

other is in the lowermost position. This lowered position is also clear from Fig. 6, at B. By loosening the nut and moving the inner element 34 in a radial manner the inner element 34 may be moved to any one of three positions, and of course the positions may be made as numerous as desired. Fig. 6, at A shows the outline of the box in the uppermost position. When the inner element 34 has been swung to the position desired, the ring may be screwed on the locking cap to fix the position. Thus, if a user desires to have the filter boxes in the lowest position so that he can see more easily, or if he desires them in some other position for some reason, adjustment can be speedily made. It will be noted that 15 the nut 44 will register nicely with each of the pockets.

A knurled knob or thumb rest 46 is fixed to the base of the element 34 for resting the thumb against the same when it is desired to screw element 35 on or off. As shown in Fig. 9, the easiest way to do this is to place the middle finger of the left hand (shown in dotted outline) in opening 33 and the opposable thumb against thumb rest 46 in proper manner to screw element 35 on 20 or off.

The purpose of this thumb rest is to make it possible to extend element 35 clear over the circumferential margin of the inner element 34, thus reducing the depth of the filter box to the smallest 30 possible amount. Without thumb rest 46 or its equivalent, in combination with opening 33, a material reduction of the depth of the filter box would be impossible, because there is nothing else to grasp when outer element 35 extends clear 35 over and beyond the circumferential margin of element 34.

The aforementioned outer element 35 is adapted to be threaded on the inner element 34 clear across its circumferential margin and is provided with a base 47. The base 47 as particularly shown in Fig. 7 has an outer circular ridge 48 and an inner circular ridge 49, the inner ridge being greater than the outer as shown in Fig. 5. The base 47 has an outer depressed portion 50 45 and an inner or central depressed portion 51. The base 47 has a plurality of holes or apertures 52 which are preferably not located at the tops of the ridges nor at the bottoms of the depressions, except in the case of the center hole, 50 for the purpose of having the greatest strength at the point of greatest advantage, and to provide a more satisfactory air passage. With the apertures on the sides of the ridges, for example, the air will pass easily into the inside 55 spaces of the filter box formed between the outer element 35 and the filter. The arrangement maintains a proper space relation between the base 47 and the filter 53 adapted to be supported in the outer element 35, which element 60 has a threaded flange 54 adapted to thread on the flange 39 of the inner element 34 to lock the filter in place against the retaining flange 40 of the inner element 34. The threaded flange 54 as shown in Fig. 5 is deeper than the flange 59, with the result that when the inner element is threaded into the outer element 35 the flange 59 may be threaded completely within the flange 54 of the outer element, depending on the thickness of the filter.

It is believed that in view of the foregoing, no further explanation is needed of the structure, operation, and advantages of the invention.

It should be understood that what I have dis- 75

closed is merely a preferred embodiment selected for purposes of illustration to illustrate the principle of my invention; and it should be understood that while I have shown certain forms of filter boxes and certain means of adjustment and removability, for example, the invention is not confined to the means shown, and these means including the ridge and depression arrangements of the filter boxes and the other features, may be modified without departing from my invention.

While I have illustrated and described therefore the preferred form of structure for carrying my invention into effect, I do not wish to be limited to the precise details of construction set forth, but desire to avail myself of such variations and modifications as come within the scope of the appended claims.

Having thus described my invention, what I claim as new and desire to secure by Letters Patent is:

1. In a respirator, a body portion and a removable filter box mounted eccentrically of the filter box on the side of said body portion and adjustable about the mounting, substantially as described.
2. In a respirator, a body portion provided with an exhaust valve and a plurality of removable filter boxes mounted eccentrically of the filter boxes on the sides of said body portion and adjustable about the mounting.
3. In a respirator, a body portion provided with an exhaust valve and a removable and adjustable filter element, and means for securing said filter element to said body portion, said means including an open flanged cap and a locking ring adapted to thread on said cap.
4. In a respirator, a body portion having an exhaust valve, a head strap having securing means, and a filter box secured thereto and having inner and outer elements and a filter, said inner element of said filter box being provided with a plurality of pockets adapted to receive said head strap securing means, the walls of said pockets forming raised portions adapted to keep the filter element spaced from the side wall of the inner element, whereby to facilitate passage of air to the interior of the body portion, after filtration.
5. In a respirator, having a body portion, an exhaust valve, and a filter box having inner and outer elements, the combination of a flanged

locking cap having an opening and adapted to secure said filter box to said body portion, and a thumb rest on said inner element, said cap opening and said thumb rest being adapted to provide engaging means for a finger and thumb of one hand to facilitate attachment and detachment of said inner and outer elements. 5

6. In a respirator, a body portion and a filter element, said filter element comprising a plate eccentrically mounted on said body, a filter and filter retaining means detachably connected to said plate and means for securing said filter element in adjusted position about said eccentric mounting. 10

7. In a respirator, a body portion and a filter box secured thereto, said filter box comprising an inner element attached to the body portion, an outer element detachably connected to the inner element, and a filter element secured between said inner and outer elements at the periphery thereof, said outer element including a perforated plate completely covering the filter element and provided with means engaging portions of said filter element remote from the periphery to maintain the same out of contact 20 with the major portion of said perforated plate, substantially as described. 25

8. In a respirator, a body portion and a filter box secured thereto, said filter box comprising an inner element attached to the body portion, an outer element detachably connected to the inner element, and a filter element secured between said inner and outer elements, said outer element including a concentrically corrugated plate completely covering the filter element and provided with a plurality of perforations and means on the inner element remote from the periphery thereof for spacing the filter element therefrom. 30 35

9. In a respirator, a body portion and a filter box secured thereto, said filter box comprising an inner element attached to the body portion, an outer element detachably connected to the inner element, and a filter element secured between said inner and outer elements, said outer element including a concentrically corrugated plate completely covering the filter element and provided with a plurality of perforations and a plurality of outwardly extending portions on the inner element remote from the periphery thereof for spacing the filter element therefrom. 40 45 50

HARVEY S. COVER.
